BINDER

Harvey E. Goldblatt, Chicago, Ill.

Application February 15, 1937, Serial No. 125,675

11 Claims. (Cl. 281—19)

The present invention relates to improvements in binders, and particularly binders of the type in which the contents are separable from the cover, whereby the former may be renewed or replaced as required.

It has been found desirable to manufacture memorandum books, note books, desk pads, and the like, as units, comprising a cover and a separable filler, which may be readily secured to and removed from the cover. Usually the filler is a relatively small sized pad comprising a plurality of sheets of paper bound together at one edge and provided with perforations near that edge whereby the sheets may be torn off. The cover 10 may take the form of a book having a back and two covers hingedly mounted thereto, or a pad adapted to be placed on a desk and comprising a relatively heavy base, a back section and a flap hingedly secured to the latter.

20 The primary object of the present invention is to provide a simple and inexpensive mounting for a separable filler and cover.

Another object of the invention is to provide an improved mounting means for a separable 25 filler and cover, so constructed that the filler may be readily and simply secured to and removed from the cover, and yet firmly held against twisting or slipping when properly secured to the cover.

30 A further object of the invention is to provide a mounting that is relatively light, but sturdy, in construction and one that does not render the assembled unit either bulky or unsightly.

Other objects and advantages of the present 35 invention will become apparent from the ensuing description of a preferred embodiment and modifications thereof.

In the course of the description, reference will be had to the accompanying drawings in which:

40 Fig. 1 is an exploded perspective view of a separable filler and cover in the form of a desk pad constructed in accordance with the present invention;

Fig. 2 is a partial longitudinal cross section 45 view through the assembled unit showing the filler secured to the cover and is taken on the line 2—2 of Fig. 3;

Fig. 3 is a partial transverse cross section view of the assembled unit and is taken along the line 50 3—3 of Fig. 2;

Fig. 4 is a top plan view of an assembled filler and cover provided with a slightly different form of mounting means;

55 Fig. 5 is an exploded perspective view of a mod-

ified form of construction illustrated as applied to a memorandum book;

Fig. 6 is a partial cross section view of the cover and filler taken along the line 6—6 of Fig. 5;

Fig. 7 is a partial perspective view, also partially in section, of a filler provided with a modified form of one of the complementary mounting portions that may be utilized in place of that shown in Fig. 5;

Fig. 8 is an exploded partial perspective view 10 of a further modification of the invention;

Fig. 9 is a longitudinal partial cross section view of the modification of Fig. 8 showing the parts in assembled relation, and is taken on line 9—9 of Fig. 10; and

Fig. 10 is a transverse partial cross section view 15 of the modification of Fig. 8, also showing the parts in assembled relation and is taken along line 10—10 of Fig. 9.

Referring first to Figs. 1, 2 and 3, in which a 20 preferred embodiment of the present invention is illustrated, there is provided a binder comprising a cover 10 and a filler 12 adapted to be detachably secured thereto. The term cover is used generically herein to designate any book-like 25 construction, such as a desk pad, memorandum book, check book, or the like, constructed in accordance with the present invention.

In the present instance the invention is shown applied to a cover comprising a desk pad 14 having secured thereto a vertically extending back section 16, to which is hingedly mounted a flap 18 adapted to cover the filler 12 when the flap is thrown to its forward position. The desk pad may be constructed in any suitable fashion and is illustrated particularly in Figs. 2 and 3 as comprising a relatively heavy base plate 20, to the bottom of which is secured a piece of soft textile 22, such as felt, to prevent the base plate from scratching its supporting structure.

The desk pad is provided with a suitable cover 24, preferably made of imitation leather and substantially surrounding the top and sides of the base plate 20. The cover is turned in around the bottom, as indicated at 26, to provide a uniform outer surface as well as prevent loosening of the textile 22 from the bottom.

The back section 16 and flap 18 are made of relatively heavy strips 28 and 30, preferably made of some material such as cardboard. The two sections are separated by a relatively narrower and weaker section 32 about which the flap may be turned. The back section and flap are covered by and secured to the pad 14 by suitable covers 34 and 36 substantially surrounding 55

these members. The covers are provided with end portions 38 extending between the outer cover 24 and base plate 20 through an opening 40 formed in the cover 24 immediately below the vertical back section 16.

The filler pad 12 consists of a considerable number of sheets of paper 42 suitably bound at end 44 in any well known manner. The sheets are perforated at 46 so that they may be readily detached from the pad whenever desired. The mounting means of the present invention comprises opposed complementary mounting members 48 and 50 secured to the inner side of back section 16 of the cover and the bound end 44 of the filler pad, respectively. The filler with its mounting member 50 is adapted to be inserted directly into the mounting member 48, as will appear more fully hereinafter.

The mounting member 48 secured to the cover 20 comprises a substantially U-shaped member secured to the back section 16 by a plurality of rivets 54 passing through the vertically disposed portion 56 connecting together the opposed and substantially parallel portions 58 and 60 of the U-shaped member. The rivets 54 do not disturb the external appearance of the cover 34, for the reason that they do not pass therethrough, as shown in Fig. 2.

The substantially parallel portions 58 and 60 are made slightly resilient and extend away from the back section 16 substantially at right angles thereto, although, as more clearly shown in Figs. 2 and 3, the upper portion 58 is provided with an angular portion 62 extending toward the lower horizontal portion 60. The purpose of this construction is to decrease somewhat the area of engagement between the upper portion 58 and the filler, so that the latter may be more readily removed from the cover. The area of contact 40 between the substantially U-shaped mounting member 48 and the filler unit is further reduced by constructing the parallel portions 58 and 60 of the latter with substantially symmetrical cut away portions 64 so that the members have 45 shapes somewhat similar to that of a trapezoid.

In order better and more readily to secure the removable filler unit to the cover, the lower parallel member 60 of the mounting member 48 is provided with a lip 66 that extends forward further than the upper parallel portion. The upper parallel portion 58 may be strengthened by providing it with a beaded edge 68.

The mounting members 48 and 50 are provided with complementary interengaging substantially rectangular projections 70 and 72, respectively. Member 50 is secured to the top of the filler unit 12 by claw-like extensions 74 formed at its ends and suitably driven into the unit. These projections 70 and 72 extend substantially transversely to the members upon which they are formed and are located substantially centrally thereon. It may be seen from Fig. 2 that the location is such that the end 44 of the filler abuts against the connecting section 56 of the U-shaped member 48.

From the above description it is apparent that the filler unit 12 with the complementary mounting member 50 attached thereto may be readily inserted into the U-shaped mounting member 48 and just as easily removed. The construction of the lower portion 60 of the mounting member with the extending lip 66 and the upper portion 58 with its front edge 68 beaded, simplifies the insertion. The filler pad is placed on the lip at 75 an angle so that the top side of the bound end

rests under and against the rounded upper portion. Since the portions 58 and 60 are somewhat resilient, it is a simple matter to insert the filler into place from this position.

Once inserted in place, the complementary projections 70 and 72 are held in abutting relation, as shown in Figs. 2 and 3, by the resiliency of the parallel portions of the U-shaped members. The location of these projections so that the filler abuts the connecting portion 56 of the U-shaped portion, provides additional restraint against slipping or twisting of the filler.

One of the advantages of the described arrangement is that the filler unit may be inserted directly into the cover without the manipulation of locking means or necessity of sliding it in from one side.

The above described mounting means may be modified, as shown in Fig. 4, for use with wider and larger books or pads. The parallel portions 58 and 60 are made somewhat larger and the former is provided with a plurality of projections 76. These are adapted to engage a plurality of complementary projections formed on mounting member 50 which, however, are not shown in this figure.

In the modified form of the present invention shown in Fig. 5, the cover 10 is of book form and comprises a central back section 16 and a pair of flaps 18 hingedly mounted thereto. These may be of any suitable construction and is illustrated as being constructed after the manner of the back section and flap of the previously described modification. The back section and flaps are constructed of sections 28 and 30 of relatively 35 heavy sheet material and are separated by the weakened sections 32, so that the flaps may be moved easily to close the book. The back section and flaps may likewise be provided with 40 suitable imitation leather covers 34 and 36.

The modified mounting means comprises a substantially U-shaped resilient mounting member 80 secured to the inside of back section 16 and a second substantially U-shaped member 82 secured to the bound end of filler 12. The U-shaped member 80 has its connecting portion 86 secured to the back section by rivets 88, and the opposed parallel sections 90 and 92 extend away from the back section substantially at right angles thereto. The parallel sections have 50 trapezoidal shapes as their outer corner portions are cut away along a diagonal line, as indicated at 94, and are provided with rectangular projections 96 extending toward each other.

The mounting member 82 extends substantially 55 the entire width of the filler. The connecting portion 98 thereof fits against the bound end of the filler and the opposed parallel portions 100 and 102 are secured to the filler by a plurality of projections 104 forced into the filler. The parallel portions are provided with rectangular projections 106 also extending toward each other.

When the filler with its mounting member 82 is inserted into the U-shaped mounting member 80 on the cover, the complementary projections 96 and 106 are brought into engagement by the resiliency of the parallel portions 90 and 92 on which the former are formed.

The insertion of the filler 12 into the cover 10 of the modification just described is accomplished in substantially the same manner as previously described, and the construction has the same desirable features.

In Fig. 7 there is illustrated a modified form of mounting member which may be attached to the 75

filler and used with a cover mounting member of the type last described. In this figure the filler 12 is provided with a pair (only one of which is shown) of mounting members 110 secured to opposite sides of the filler by a plurality of inwardly extending projections 112. An inwardly projecting portion 114, similar to projections 96, is formed on each of these members. When the filler and its mounting member are inserted into the U-shaped cover mounting member 80 of Figs. 5 and 6, the filler is firmly secured in place by the complementary projections, and the end of the filler which fits against the connecting portion 86.

The modification illustrated in Figs. 8, 9 and 10 also comprises a pair of interfitting substantially U-shaped mounting members secured to the cover and filler, respectively. The resilient mounting member 116 has its connecting portion 118 secured to the back section by rivets 120, and the opposed parallel portions 122 and 124 are each provided with a plurality of hemispherical projections 126 extending toward each other. The connecting portion is also provided with a pair of spaced apart projections 128 extending away from the back section.

The mounting member 130 has its opposed parallel portions 132 and 134 secured to the filler 12, which is illustrated as having a binding 136 of paper, or the like, by a plurality of inwardly extending projections 137. Instead of being provided with complementary projections adapted to engage projections 126, the parallel portions 132 and 134 are provided with a plurality of perforations 138 into which the projections are adapted to extend when the filler is inserted into the cover. The bottom portion 140 of mounting member 130 is provided with complementary projections 142 into which the projections 128 extend.

The purpose of providing the bottom portions 118 and 140 with complementary projections, is to decrease further the possibility of twisting or slipping of the filler. Once the filler is inserted in place, it is restrained against movement by interengaging portions on three of its five sides and is, therefore, held in place firmly.

It should be evident from the above that the present invention is susceptible of various modifications. For instance, while the U-shaped mounting members secured to the covers have been described as constructed of resilient material, they may be constructed only in part of resilient material. It is contemplated that only one of the opposed parallel portions thereof need be made of resilient material, and that other forms of interengaging readily detachable mounting members may be used.

I claim:

1. A binder comprising a separable cover and filler, a single unitary substantially U-shaped channel secured centrally of the inside of the back section of said cover provided with a transversely extending projection on one of the parallel portions thereof, and means including a member secured centrally of said filler and provided with a complementary transversely extending projection adapted to engage that on said parallel portion when the filler is inserted into said cover.

2. A binder comprising a separable cover and a filler, a mounting member secured centrally of and having a pair of opposed single unitary substantially parallel portions extending at right angles from said cover, said parallel portions being provided with transversely extending projections, and means secured centrally of said filler

provided with complementary portions adapted to engage the projections on said mounting member for detachably securing said filler to said cover, said mounting member and last mentioned means being so constructed and arranged that the latter may be directly inserted into the former by movement in the direction of the back section.

3. A mounting for a filler pad adapted to be detachably secured to the back section of a cover, including in combination, a single unitary member secured centrally of and provided with a resilient portion extending substantially at right angles from said back section and having transversely extending projections, and a single unitary member secured centrally of said filler pad provided with projections similar to those on said portion extending from the back section, said members and projections being so constructed and arranged that the projections resiliently engage each other and the bound end of the pad abuts against the back section whereby the filler pad is held to said cover when the latter is inserted into said resilient portion.

4. A mounting for a filler bound at one end adapted to be detachably secured to the back section of a cover, including in combination, a substantially U-shaped mounting member secured to the inside of said back section with the opposed parallel portions thereof extending away from said section, a substantially rectangular transversely extending projection formed centrally on the upper of said parallel portions, a relatively small member secured to the central part of the upper side of the bound end of said filler and formed with a complementary projection, said projections being adapted to interengage and the bound end of the filler to abut against the portion of the U-shaped mounting member adjacent the back section when the filler is inserted into said U-shaped mounting member.

5. A mounting for a filler adapted to be detachably secured to the back section of a cover, including in combination, a substantially U-shaped mounting member secured to the inside of said back section with opposed parallel portions thereof extending away from said section, a plurality of substantially rectangular transversely extending projections formed on the upper of said parallel portions, a member secured to the upper side of said filler and formed with complementary projections, said projections being adapted to interengage and firmly hold said filler in said mounting member when inserted therein.

6. A binder comprising a cover, a filler, and means for detachably mounting said filler in said cover, said means including a resilient substantially U-shaped channel secured to the inside of said cover, a U-shaped channel secured to one end of said filler and adapted to be inserted into said first mentioned channel, and interengaging portions on said channels adapted to maintain said channels in fixed relation to each other when the one is inserted into the other.

7. A mounting for a filler adapted to be detachably secured to the back section of a cover, including in combination, a substantially U-shaped mounting member secured to the inside of said back section with the opposed parallel portions thereof extending away from said section, a substantially rectangular transversely extending projection on each of said parallel portions, a substantially U-shaped member secured to one end of said filler and formed with complementary projections on its opposed parallel portions, said projections being adapted to interen-

gage and firmly hold said filler in place when inserted into said U-shaped mounting member.

8. A mounting for a filler adapted to be detachably secured to the back section of a cover, including in combination, a substantially U-shaped mounting member secured to the inside of said back section with the opposed parallel portions thereof extending away from said section, a substantially rectangular transversely extending projection on each of said parallel portions, and a member secured to each side of said filler provided with a complementary projection, said projections being adapted to interengage and securely hold said filler in place when inserted in said U-shaped mounting.

9. A mounting for a filler pad adapted to be detachably secured to the back section of a cover, including in combination, a substantially U-shaped mounting member secured to the inside of the back section with the opposed parallel portions thereof extending away from said section, a plurality of transversely extending projections on each of said parallel portions and the connecting portion, and a U-shaped member secured to one end of said filler and adapted to be inserted into said first mentioned U-shaped member, said last mentioned member being provided with complementary portions adapted to engage those on said mounting member whereby said filler is held in place against lateral displacement when inserted therein.

10. A mounting for a filler adapted to be detachably secured to the back section of a cover, including in combination, a substantially U-shaped mounting member secured to the inside of the back section with the opposed parallel

portions thereof extending away from said section, a plurality of substantially hemispherical projections extending toward each other formed on said parallel portions, a substantially U-shaped member secured to that end of said filler adapted to be inserted into said mounting member and formed with a plurality of openings on its opposed parallel portions, said openings being so located that projections on the filler extend into the openings when the filler is inserted into said mounting member.

11. A mounting for a filler adapted to be detachably secured to the back section of a cover, including in combination, a substantially U-shaped mounting member having the connecting portion secured to the inside of the back section and the opposed parallel portions thereof extending away from said section, a plurality of projections extending away from said back section formed on the connecting portion of said member, a plurality of projections extending toward each other formed on said parallel portions, a substantially U-shaped member secured to that end of the filler adapted to be inserted into said mounting member, the opposed parallel portions thereof being provided with openings into which the projections on the parallel portions of the U-shaped member extend when the filler is inserted into said mounting member, and the connecting portion thereof being provided with complementary projections into which the projections on the first mentioned connecting portion extend when the filler is inserted into said mounting.

HARVEY E. GOLDBLATT. 35
